GAME BOARD

William J. Champion, Mystic, Conn.

Application June 27, 1951, Serial No. 15,689

Term of patent 14 years

(Cl. D34—5)

To all whom it may concern:

Be it known that I, William J. Champion, a citizen of the United States, residing at Mystic, in the county of New London and State of Connecticut, have invented a new, original, and ornamental Design for a Game Board, of which the following is a specification, reference being had to the accompanying drawing, forming part thereof.

In the drawing:

Fig. 1 is a top perspective view of a game board, showing my new design;

Fig. 2 is a front elevational view of the same;

Fig. 3 is a sectional view taken on the line 3—3 of Fig. 1;

Fig. 4 is a sectional view taken on the line 4—4 of Fig. 1; and

Fig. 5 is a sectional view taken on the line 5—5 of Fig. 1.

The sliding blocks in the drawing figures are shaded to show colors.

I claim:

The ornamental design for a game board, as shown and described.

WILLIAM J. CHAMPION.
